UNITED STATES PATENT OFFICE.

HENRY REUBEL, OF NEW YORK, N. Y.

CURTAIN-FIXTURE.

1,080,479.

Specification of Letters Patent.

Patented Dec. 2, 1913.

Application filed September 28, 1912. Serial No. 722,891.

To all whom it may concern:

Be it known that I, HENRY REUBEL, a citizen of the United States, and a resident of the city of New York, borough of Manhattan, in the county and State of New York, have invented a new and Improved Curtain-Fixture, of which the following is a full, clear, and exact description.

The object of the invention is to provide a new and improved curtain fixture arranged to permit of conveniently placing the curtain rod in position on the supporting brackets to securely hold the curtain rod in place on the brackets and to allow of placing the fixture directly under an overhanging or projecting molding or the like.

For the purpose mentioned, use is made of a curtain rod having its ends provided with integral heads and brackets having tubular bearings for the reception of the said heads, the bearings being provided at the front with slits for the passage of the portion of the curtain rod adjacent the heads. Use is also made of retaining means for holding the heads against movement in the bearings.

A practical embodiment of the invention is represented in the accompanying drawings forming a part of this specification, in which similar characters of reference indicate corresponding parts in all the views.

Figure 1 is a perspective view of one end of the curtain fixture; Fig. 2 is an enlarged cross section of the same; Fig. 3 is a plan view of one end of the curtain rod.

The curtain rod A is preferably of the extension type, that is, made in two parts, one telescoping the other, and the curtain rod is also preferably formed of flat strips of sheet metal having the side edges over-turned to provide guideways on one section for the flanges of the other section to slide in. The ends A' of the curtain rod are preferably bent inward and each end terminates in a tubular integral head A² adapted to fit into a tubular bearing B' formed on an attaching bracket B provided with attaching flanges B² offset from the upper and lower ends of the bearing B' and adapted to be secured by screws, nails and other fastening means C to the window frame, door frame or other suitable support, as plainly indicated in the drawings. The tubular bearing B' of each bracket B is provided at the front with a slit or slot B³ extending from one end of the bearing to the other,

and in the said slit fits the portion of the end A' adjacent the corresponding head A² so that the head A² can be moved into position in the bearing B' through one end thereof, and as the said head A² and the adjacent portion of the end A' fit snugly into the bearing and into the slit B³, it is evident that a firm, non-wabbling connection is had between the rod A and its supporting brackets B. A spring D extends within the bearing B' of each bracket B and is adapted to pass through the head A² when the latter is placed in position in the bearing B', and the spring D is provided with an angular offset D' terminating in a flange D², preferably fastened by an eyelet E to one of the attaching flanges B² of the bracket B. One of the fastening means C passes through the eyelet E, as indicated in Figs. 1, 2 and 3. The free end D³ of the spring D is V-shaped and is adjacent the corresponding end of the head A² at the time the latter is engaged with the bearing B' so that the head A² is held against movement in one direction by abutting against the angular offset D', and is held against movement in the opposite direction by the V-shaped terminal D³. Thus accidental movement of the head A² in the bearing B' in either direction is prevented.

It will be noticed that when placing the curtain rod A in position on the brackets the heads A² are slipped over the terminals D³ and then into the bearings B', it being understood that the resiliency of the springs D permits the springs D to bend sufficiently for passing the terminals D³ through the heads A², and after the heads have passed the terminals D³ the springs return to their normal position by their own resiliency, as will be readily understood by reference to Figs. 1 and 2. It will also be noticed that by constructing the brackets B in the manner described, the brackets may be placed upside down directly under an overhanging or projecting molding, as indicated in Figs. 1 and 2, to permit of engaging the heads A² with the bearings B' and the springs D from underneath at the same time securely holding the heads A² in position in the bearings against downward movement.

The curtain fixture shown and described is composed of comparatively few parts, not liable easily to get out of order, and the curtain fixture can be cheaply manufactured. The user can readily fasten the

brackets B in position on the window frame, door frame or other support and place the curtain rod A into or out of engagement with the brackets, as previously explained. 5 The curtain rod A is preferably concave at its outer face, as indicated in Fig. 2, to heighten the appearance of the curtain rod and to increase the strength thereof.

In manufacturing the curtain rod A the 10 upper and lower flanges of each rod section are doubled up at the head A² (see Fig. 2) so as to reinforce the tubular head at top and bottom and at the same time form smooth, rounded-off top and bottom edges 15 to permit of conveniently engaging the heads A² with the bearings B.

Having thus described my invention, I claim as new and desire to secure by Letters Patent:

20 1. A curtain fixture, comprising a curtain rod provided at its ends with tubular heads, brackets having bearings for the reception of the said heads, and springs attached to the said brackets and extending within the 25 said bearings and through the said tubular heads.

2. A curtain fixture, comprising a curtain rod provided at its end with tubular heads, brackets having bearings for the reception 30 of the said heads, and springs attached to the said brackets and extending within the said bearings and through the said tubular heads, the free ends of the springs having offsets adjacent the ends of the heads.

35 3. A curtain fixture, comprising a flat curtain rod having its ends bent into tubular heads, brackets each having a tubular bearing and integral attaching members, the

bearing being split at the front and in the direction of the length of the bearing, the 40 said heads engaging the bearings on the said brackets and the portions of the rod adjacent the heads fitting into the splits of the bearings, and a spring secured at one end to one of the attaching members of a bracket 45 and extending within the bearing of the bracket and through the tubular head, the free end of the spring having an offset immediately adjacent the end of the head.

4. A curtain fixture, comprising a flat curtain rod having its ends bent into tubular heads, brackets each having a tubular bearing and integral attaching members, the bearing being split at the front and in the direction of the length of the bearing, the 50 55 said heads engaging the bearings on the said brackets, and the portions of the rod adjacent the heads fitting into the splits of the bearings, and a spring for each bracket and having one end attached to one of the attaching members of the bracket, the spring having an angular connection with the attached end adjacent one end of the bracket bearing, the spring extending through the bracket bearing and through the corresponding head, and the spring having a V-shaped 60 65 terminal immediately outside the corresponding end of the tubular head.

In testimony whereof I have signed my name to this specification in the presence 70 of two subscribing witnesses.

HENRY REUBEL.
